J. F. COURSON.

DRAFT GEAR.

APPLICATION FILED FEB. 15, 1917.

1,277,870.

Patented Sept. 3, 1918.

UNITED STATES PATENT OFFICE.

JOHN F. COURSON, OF PITCAIRN, PENNSYLVANIA.

DRAFT-GEAR.

Specification of Letters Patent.

Patented Sept. 3, 1918.

1,277,870.

Application filed February 15, 1917. Serial No. 148,719.

To all whom it may concern:

Be it known that I, JOHN F. COURSON, a citizen of the United States, residing at Pitcairn, in the county of Allegheny and State of Pennsylvania, have invented certain new and useful Improvements in Draft-Gears, of which the following is a specification.

My invention is an improvement in draft gears for railway cars, etc., and it has for its object to provide a draft gear utilizing friction and spring resistance, of simple construction and high efficiency, designed to utilize the wedging and releasing action of wedge blocks arranged between a central buffering member and surrounding friction members, an inclosing open ended casing, a spring, and mechanism mounted within the car frame and so connected with the draw bar as to transmit buffering and pulling strains to the car underframe.

The objects in view are to provide, in a gear of this class, for easy mounting within the car frame, a direct connection with the draw bar by means of slotted straps or lugs, operating in connection with keys and directly engaging the casing for forward movement from normal position and returning it thereto at the termination of pulling strains.

Preferred constructions of the invention, including the several detail parts, are more fully hereinafter described and illustrated in the accompanying drawings, in which—

Figure 1 is a longitudinal vertical sectional view of a complete gear as assembled, indicated by the section line I, I, of Fig. 2, the parts being shown in normal extended position.

Fig. 2 is a horizontal sectional view indicated by the line II, II, of Fig. 1.

Fig. 3 is a cross-sectional view indicated by the line III, III, of Fig. 1.

Fig. 4 is a view similar to Fig. 1, but in sectional construction on the line IV, IV, of Fig. 2, showing the parts in compression, under pulling strains.

Fig. 5 is a detail perspective view of the casing detached.

Fig. 6 is a similar view of the apertured cross-head mounted between the center sills.

Fig. 7 is a partial sectional view similar to Fig. 2 but showing a modified construction of the arrangement between the side bar and the casing.

In the drawings, 2 represents the draw bar of a coupler connected with the side bars 3, 3, by a transverse key 4 which passes through the draw bar and through longitudinally arranged slots 5, 5, of bars 3. Slots 5 are provided for clearance of key 4 in buffering and for key 6 in pulling, the bars 3 positively engaging the lugs of the casing, as hereinafter described.

Key 6 extends transversely through slots 7, 7, of the center sills 8 and bears forwardly against the sills and abutment stops 9, 9, thereof, providing a rigid bearing for the central wedge 10 in pulling. Said wedge is preferably provided with a transverse middle slotted portion, through which key 6 passes, the wedge extending over the key above and below and providing a good supporting bearing for mounting the wedge in central position.

The friction receiving member of the gear 75 is a casing 11, generally cylindrical in form, preferably having a slight taper inwardly toward its rear end, and in the main construction being provided with laterally extending ears or lugs 12, 12.

These lugs extend through or into sockets 5' of bars 3, the bars thus embracing the lugs and holding the casing in normal position, being adapted to transmit forward movement to it in pulling, and to retract it 85 to normal position in releasing after pulling strains. The rear end portions of the bars 3 are provided with a transverse key 13 which bears in normal position backwardly against a transverse abutment 14 which is riveted 90 or otherwise secured between the center sills 8.

Abutment 14 is provided with a slotted housing 15 between the upper and lower sides of which the key 13 moves forwardly 95 in pulling, and in which it seats in buffering, as will be readily understood.

Housing portion 15 also provides by its front faces a bearing for spring plate 16, which also has a slotted engagement with 1' the front edge portion of key 13, and by which the spring plate is pressed forwardly in pulling, as in Fig. 4. In normal position as in Figs. 1 and 2, the spring plate seats 1 backwardly against the housing 15.

Within the casing 11 and engaging the inner faces thereof are friction shoes 17, preferably in an assembled segmental shaped

series, each of which is provided at its inner portion with an inwardly extending wedge projection 18.

Between the faces of central wedge 10 and the inner faces of friction shoes 17 are interposed expanding wedges 20, and between the inner wedge portion 18 of friction shoes 17 is interposed a separating or expanding wedge 21. Said wedge bears by its front portion against the rear ends of wedges 20 and co-operates with these parts in expanding the friction shoes 17 equally throughout their length against the inner face of casing 11.

15 Between the rear ends of shoes 17 and spring plate 16 is interposed a spring or springs 22, 22'. The spring resistance, by these elements, may be varied to suit the conditions of use, and either a single spring 20 of the desired strength, or a plurality of springs may be utilized, whereby to transmit pressure directly between the rear forwardly moving cross key 13 and the relatively stationary friction shoes 17 in pulling, or between the rearwardly moving friction shoes and the relatively stationary key 13 and abutment 14 in buffering.

Between the center sills 8, immediately behind casing 11, and providing a rigid abutting bearing for the casing in normal position, and during buffering strains, I provide the apertured cross-head 23, shown in detail in Fig. 6. This cross-head fits against the center sills and is fixedly bolted or otherwise secured thereto, and is provided with a central clearance opening 24 for the spring or springs 22, 22', and also at each side thereof with clearance openings 25, 25, for the side bars 3, 3.

40 The cross-head fixedly braces the center sills, provides a bearing abutment for the casing, and a mounting for the side bars and springs.

A lower plate 26 extending across from one side sill to the other is also preferably provided for supporting the casing 11, in connection with the engagement of lugs 12 with the slotted side bars.

45 In Fig. 7, I show a somewhat modified construction in which the lugs 12 of the casing are omitted, leaving it continuously cylindrical on the exterior, and the side bars 3^a are provided with attached lugs or abutments 12^a, 12^a, which bear directly against the rear and front end portion of the casing 11^a at each side.

In such construction the cross-head 23 is omitted, the bars 3^a and rear lugs 12^a taking the buffering thrust.

50 In operation, the gear is effective to generate a high degree of resisting friction either in buffering or pulling, by expansion of the friction shoes 17 and their frictional engagement with the casing 11, in connection with the spring 22.

The friction members therefore are operative throughout practically the entire interior of the casing, their action being substantially the same in either pulling or buffering movements.

70 Thus in buffering, rearward movement of the draw bar and corresponding inward movement of wedge 10 will distend the wedge and friction elements and will move them backwardly, compressing the springs 75 with relation to the relatively stationary casing 11, the side bars 3 remaining stationary and keys 4 and 6 passing backwardly through slots 5.

In pulling, draw bar 2 and key 4 will 80 exert forward pressure upon side bars 3 which in turn, by key 13 and spring plate 16, will compress spring 22, the casing 11 being simultaneously carried forward by its engagement with the bars 3.

85 Central wedge 10, being resisted by key 6, will exert expanding and resisting action against the wedge and friction shoe mechanism, generating friction between the shoes and the casing in the same manner. Upon 90 release of pressure in either direction the parts will assume their normal position.

What I claim is:

1. A draft gear consisting of a tubular casing, a bearing abutment therefor, friction shoes within the casing, a central pressure bar, an abutment therefor, a drawbar operatively related to the pressure bar, and means operable to exert pressure on the friction shoes through the rear end of the casing toward the pressure bar and connected with the casing and drawbar.

95 2. A draft gear consisting of a tubular casing, a bearing abutment therefor, friction shoes within the casing, a central pressure bar, an abutment therefor, a drawbar operatively related to the pressure bar, a forwardly movable abutment, a spring inserted between said abutment and the friction shoes, and side bars connected with said 100 abutment and the drawbar and having positive engagement with the casing.

110 3. In combination with a forwardly movable rear abutment and a rearwardly movable front abutment, an intervening open-ended casing, a rear bearing therefor, friction creating mechanism within the casing 115 engaging the front abutment, a resilient element between the friction creating mechanism and the rear abutment, a drawbar, and means connecting the rear abutment there-

120 with.

125 4. In combination with a forwardly movable rear abutment and a rearwardly movable front abutment, an intervening open-ended casing, a rear bearing therefor, friction creating mechanism within the casing 130 engaging the front abutment, a resilient element between the friction creating mechanism and the rear abutment, a drawbar, and

means connecting the rear abutment with the drawbar and having positive engagement with the casing.

5. In combination with car framing, a transverse apertured abutment, a casing engaging said abutment, friction creating mechanism within the casing embodying a central pressure bar, a forward abutment for said bar, a rear abutment and a forwardly movable key, a spring between said key and the friction mechanism, a drawbar, and slotted side bars connecting said key with the drawbar and engaging the casing on either movement.
- 15 6. In combination with car framing, a rear abutment, a rear transverse key seating against said abutment, a forward key having slotted engagement with the car framing and engaging against abutments thereof, an intervening transverse abutment,
- 25 a tubular casing in front of said abutment, friction creating mechanism within said casing, a central wedge therefor engaging said forward key, a spring between the friction mechanism and the rear key, and side bars connecting the rear key with the drawbar and having forward and backward engagement with the casing.
- 30 7. A draft gear having resistance keys adapted to engage a car framing, a longitudinally movable open ended casing, longitudinally movable expansible friction creating mechanism within the casing, resistance elements between the opposite ends of said mechanism and said keys, and members connecting one of said keys with the casing and adapted to be connected to a drawbar.
- 35 In testimony whereof I hereunto affix my signature.

JOHN F. COURSON.
